E. HEYDON

POLE REINFORCING SLEEVE

Filed May 5, 1924

UNITED STATES PATENT OFFICE.

EDWARD HEYDON, DECEASED, LATE OF INDIANAPOLIS, INDIANA; BY EMMA HEYDON, EXECUTRIX, OF INDIANAPOLIS, INDIANA, ASSIGNOR TO EMMA HEYDON, OF INDIANAPOLIS, INDIANA.

POLE-REENFORCING SLEEVE.

Application filed May 5, 1924. Serial No. 711,164.

It is the object of the present invention to provide a pole-reenforcing sleeve which can be put on and taken off the pole with relatively great ease; which is capable of use 5 on portions of the pole where the diameter changes as well as on portions thereof where the diameter is uniform; which is formed with interlocking parts which may be interengaged and disengaged by relatively 10 short longitudinal movement between such parts; which has interlocking parts which interlock firmly regardless of any reaction from a pole or other part within the sleeve, so that the locking together of the sleeve- 15 parts will be independent of the pole; which serves to tighten the locking action as the interlocking parts move together into their interfiting relation; and which has a safety device for holding the parts locked together 20 against accidental displacement.

The present invention is to some extent a development of and improvement on that set forth in the co-pending application Ser. No. 622,862, filed March 5, 1923, by the same 25 inventor.

In carrying out the present invention, the sleeve is made of a plurality of parts which together form a complete sleeve; and these sleeve-parts are provided at their meeting 30 edges with interlocking members which are engageable and disengageable by a comparatively short longitudinal movement of one sleeve-part relatively to another. These interlocking members are most conveniently 35 tongue-sections and groove-sections, longitudinally spaced apart so that the sections of each set of interlocking parts have spaces between them of sufficient length to receive the sections of the other set. This, however, 40 as so far described is set forth in the aforesaid co-pending application.

By the present improvement, however, several independent developments have been made. One of these is the making of the 45 interlocking parts wedge-shaped, so that they tighten the parts relatively as they enter one into the other. Another is the making of the tongue-sections and the groove-sections of such nature as to preclude their

withdrawal or putting together other than 50 by relative longitudinal movement between the respective parts, regardless of whether or not there is a pole within the sleeve; a third feature is the provision of locking fingers for preventing accidental relative 55 longitudinal movement to separate the parts.

The accompanying drawing illustrates the invention: Fig. 1 is a vertical sectional view through a multi-section tubular steel pole equipped at various points with pole-reenforcing sleeves of the invention, the two lower sleeves being shown as filled with grout, while the uppermost sleeve is shown as snugly fitting the pole without grout; Fig. 2 is an enlarged perspective view of the lowermost sleeve shown in Fig. 1, with the two sleeve-parts interlocked; Fig. 3 is a section on the line 3-3 of Fig. 2, but before the grout has been put in place; Fig. 4 is an enlarged elevation of the uppermost sleeve of Fig. 1, with the two sleeve-parts displaced sufficiently to unlock them; and Fig. 5 is a plan of the sleeve shown in Fig. 4.

The pole shown is a multi-section steel pole, having a lower part 10 set in the ground 11 but projecting upward therefrom, an intermediate part 12 the lower end of which projects some distance into the upper end of the section 10, and an upper section 13, the lower end of which projects into the upper end of the section 12. This pole has several well-defined points where it is most apt to corrode and become weakened by natural conditions, due to the retaining of moisture in contact with the metal. These are at the ground line 11 for the section 10, and at the upper ends of the sections 10 and 12 for the sections 12 and 13 respectively. Therefore, it is at these points that the pole is most apt to need reenforcing sleeves, which may be put around the pole at these points, as indicated in Fig. 1.

The reenforcing sleeve may fit the pole fairly snugly, with no material intervening space, as the uppermost sleeve 14 is shown in Fig. 1, or may be slightly spaced from the pole by internal lugs 15 on the sleeve,

as the intermediate and lowermost sleeves 16 and 17 are shown in Fig. 1, in which latter cases the intervening space between the sleeve and the pole may be filled with grout 5. The lowermost sleeve 17 is of the same size at both top and bottom, because it is not intended to extend past a pole-joint; but the two sleeves 14 and 16 are of smaller diameter at the top than at the bottom, because they co-operate with the pole at joints, and at each joint the pole is smaller above the joint than it is below the joint. This two-diameter feature is made possible by the invention of the present application and 15 of the aforesaid co-pending application. The one-diameter sleeve is shown in Figs. 2 and 3, and the two-diameter sleeve in Figs. 4 and 5; but either can be used, as conditions require. As so far described, except for the two-diameter feature, the structure is old, and the invention is applicable to any of the types of sleeves shown, whether one-diameter or two-diameter sleeves, and whether with or without the internal lugs 15. 20 Each sleeve 14, 16, and 17 is made of a plurality of parts 21 and 22. Most conveniently these parts are halves, and duplicates, so that two similar parts are used to form a complete sleeve, each part extending for 30 180° around the pole circumference. Each sleeve-part at one longitudinal edge has a discontinuous tongue formed by a plurality of spaced tongue-sections 23, equally spaced. Preferably there is a tongue-section at each 35 end, so that there is one more tongue-section than space. On the other longitudinal edge, each sleeve-part has a plurality of spaced rib-sections 24, which are provided with grooves 25 of the proper size and shape 40 to receive the tongue-sections 23. The rib-sections correspond in number to the tongue-sections, and are correspondingly spaced. Each space between adjacent tongue-sections or rib-sections is conveniently longer 45 than a tongue-section or rib-section itself, for clearance in assembling and disassembling. Conveniently, all the tongue-sections and all the rib-sections on a sleeve-part are coplanar, lying in the same diametrical plane. 50 Instead of having the tongue-sections 23 and the grooves 25 radial, as in the aforesaid co-pending application, they are arranged so that they interlock against relative radial movement. In that way, the 55 two sleeve-parts are prevented from being separated, and the tongue-sections are prevented from being separated from or inserted in the groove 25, by other movements than longitudinal movement between the two sleeve-parts. Conveniently, this individual interlocking between a tongue-section and its mating groove is obtained by making the tongue and the groove substantially perpendicular to the radii passing through them, as is clear from Figs. 3 and 5, and by

providing the rib-sections containing the grooves with bases which lie behind the bases of the tongue. In other words, in this convenient arrangement the tongues 23 are made to extend out slightly radially and then to bend tangentially; and the rib-sections containing the grooves are made to extend outward substantially radially past the bases of the tangential part of the tongues, then to extend tangentially, then to extend inwardly, and then to hook back tangentially toward their first-named parts. With this arrangement, the tongue-sections cannot be separated from the grooves in the rib-sections other than by relative longitudinal movement between them. 70 75 80

Further, the tongues 23 are made longitudinally wedge-shaped, as is clear from Fig. 4; and the grooves in the rib-sections 24 are made matingly wedge-shaped. The inclined surface is formed on the free edge of the tongue, and on the mating part of the groove, so that the wedging action between such parts will serve to draw the two sleeve-parts together. These inclined or wedging surfaces are best shown in Fig. 4, where each tongue-section 23 is shown with its inclined edge surface 26, and each rib-section 24 is shown with an inclined base 27 for co-operating with the edge 26 of the tongue. 90 95

With the arrangement as thus described, it is possible to assemble and disassemble the sleeve, whether on a pole or not, by displacing the two sleeve-parts longitudinally by only the length of a tongue-section or rib-section. In other words, with the tongue-sections and rib-sections similarly spaced, and with a section rather than a space at each end of each sleeve-part, the longitudinal displacement between the two sleeve-parts necessary to assemble or disassemble the sleeve is the invert of twice the number of tongue-sections or rib-sections minus one—that is, if there are four tongue-sections, the necessary displacement is only one-seventh of the sleeve-length, as shown in Fig. 4. By making this displacement, the two sleeve-parts can be put together so that the tongue-sections of each sleeve-part are in alignment with the grooves in the rib-sections of the other sleeve-part, whereupon the two sleeve-parts may be moved relatively longitudinally to lock the two sleeve-parts together. This makes it necessary to drive a sleeve-part only a fraction of what was formerly required in order to lock it to or unlock it from the other sleeve-part, so that the breakage is thereby greatly reduced, and the liability of encountering obstructions in movement is correspondingly reduced. 100 105 110 115 120 125

This assembling and disassembling involves an interlocking between tongue and groove, independent of any action of the pole within the sleeve, because of the individual interlocking of each tongue with its 130

mating groove. Further, by the wedging surfaces 26 and 27, the two sleeve-parts are firmly pulled together, and tightened on the pole if the pole is in place; but the wedging action is independent of the presence of a pole in the sleeve.

When the sleeve is assembled at a joint, as are the sleeves 14 and 16 of Fig. 1, one sleeve-part is put on the pole at the joint, and the other sleeve-part is put on at the necessary distance above the joint so that the rib-sections and tongue-sections of that sleeve-part will interdigitate with those of its mate; and then the higher sleeve-section is driven downward to lock the two parts together and to keep both sleeve-parts on the upper end of the adjacent lower pole-section. The change in diameter when there is a two-diameter sleeve, as at a joint, is at a place between sections of the tongues and ribs, as is indicated in Fig. 4. When the two sleeve-parts are locked together, the grout 18, if it is used, may be poured in place.

When it is desired to separate the two sleeve-parts, it is necessary to move one sleeve forward longitudinally relatively to the other only by the same distance that was required for putting them together.

In order to prevent accidental longitudinal movement to separate the two sleeve-parts, there is preferably provided on either or both sleeve-parts one or more fingers 30, near the end of a tongue-section or a rib-section, at that end thereof which must be passed by the mating rib-section or tongue-section in the separation of the two sleeve-parts. These fingers 30 normally are cut of the path of the rib-sections or tongue-sections on the other part; but after the two sleeve-parts have been put together, these fingers may be bent inward into the path of a rib-section or tongue-section on the other sleeve-part, as is indicated for the uppermost finger 30 in Fig. 2. With the finger thus bent in, the two sleeve-parts cannot be moved relatively to disengage them, until such bent-in finger has first been moved out of the way. There may be any number of such fingers; but preferably several are provided, so that in case one breaks off, another is in reserve.

The invention claimed is:—

1. A pole-reenforcing sleeve, comprising a plurality of parts which together form a complete sleeve, said parts at their meeting longitudinal edges being provided with exterior interfitting wedging tongues and grooves.
2. A pole-reenforcing sleeve, comprising a plurality of parts which together form a complete sleeve, said parts at their meeting longitudinal edges being provided with exterior interfitting wedging tongues and grooves, said tongues and grooves being

in sections so that the sleeve-parts may be put together and taken apart by relative longitudinal movement less than the length of the sleeve.

3. A pole-reenforcing sleeve, comprising a plurality of parts which together form a complete sleeve, said parts at their meeting longitudinal edges being provided with interfitting tongues and grooves which independently of the presence of a pole within the sleeve individually interlock against separation by relative diametral movement, said tongues and grooves being in sections so that the sleeve-parts may be put together and taken apart by relative longitudinal movement less than the length of the sleeve.

4. A pole-reenforcing sleeve, comprising a plurality of parts which together form a complete sleeve, said parts at their meeting longitudinal edges being provided with interfitting wedging tongues and grooves which independently of the presence of a pole within the sleeve individually interlock against separation by relative diametral movement, said tongues and grooves being in sections so that the sleeve-parts may be put together and taken apart by relative longitudinal movement less than the length of the sleeve.

5. A pole-reenforcing sleeve, comprising a plurality of parts which together form a complete sleeve, said parts at their meeting longitudinal edges being provided with interfitting tongues and grooves which independently of the presence of a pole within the sleeve individually interlock against separation by relative diametral movement, and a locking device for preventing longitudinal movement of said sleeve-parts to separate them.

6. A pole reenforcing sleeve, comprising a plurality of parts which together form a complete sleeve, said parts at their meeting longitudinal edges being provided with interfitting tongues and grooves which independently of the presence of a pole within the sleeve individually interlock against separation by relative diametral movement, said tongues and grooves being in sections so that the sleeve-parts may be put together and taken apart by relative longitudinal movement less than the length of the sleeve, and a locking device for preventing longitudinal movement of said sleeve-parts to separate them.

7. A pole-reenforcing sleeve, comprising a plurality of parts which together form a complete sleeve, said parts at their meeting longitudinal edges being provided with exterior interfitting tongues and grooves, and a locking device for preventing longitudinal movement of said sleeve-parts to separate them.

8. A pole-reenforcing sleeve, comprising a plurality of parts which together form a

complete sleeve, said parts at their meeting longitudinal edges being provided with exterior interfitting tongues and grooves, said tongues and grooves being in sections so that the sleeve-parts may be put together and taken apart by relative longitudinal movement less than the length of the sleeve, and a locking device for preventing longi-

tudinal movement of said sleeve-parts to separate them.

In witness whereof, I have hereunto set my hand at Indianapolis, Indiana, this 2nd day of May, 1924.

EMMA HEYDON,
*Executrix of the Estate of Edward Heydon,
Deceased.*
